UNITED STATES PATENT OFFICE.

JOSEPH M. CONLEY, OF GREENVILLE JUNCTION, MAINE, ASSIGNOR OF ONE-HALF TO
A. M. BIRD, OF MEGANTIC, PROVINCE OF QUEBEC, CANADA.

SIGNAL-FLAG SUPPORT.

Application filed March 19, 1923. Serial No. 626,089.

To all whom it may concern:

Be it known that I, JOSEPH M. CONLEY, a citizen of the United States, residing at Greenville Junction, in the county of Piscataquis and State of Maine, have invented certain new and useful Improvements in Signal-Flag Supports, of which the following is a specification.

This invention relates to portable signal devices, more particularly adapted for use in railway repair operations, and to signal trains approaching portions of the track which are being repaired, and has for one of its objects to provide a device of this character which may be quickly applied where required and folded to occupy a small space when not in use or when being transported or stored.

Another object of the invention is to provide a device of this character which may be readily adjusted to varying conditions of the roadbed of a railway line, without detaching any of the parts.

With these and other objects in view the invention consists in certain novel features of construction as hereinafter shown and described and then specifically pointed out in the claims, and in the drawings illustrative of the preferred embodiment of the invention.

Figure 1 is a side elevation of the improved device, partly in section, and supported from a railway rail and likewise supported from the ground adjacent to the railway line, the railway rail being in transverse section.

Figure 2 is a plan view of the parts shown in Figure 1, and partly in section.

Figure 3 is a section on the line 3—3 of Figure 2.

Figure 4 is an enlarged section on the line 4—4 of Figure 3.

Figure 5 is an enlarged section on the line 5—5 of Figure 4.

Figure 6 is a detached plan view of the base member of the improved device.

Figure 7 is a detail illustrating the manner of holding the signal flag in its lowered or operative position.

Figure 8 is a detail illustrating a modification of the construction.

The improved device comprises a base plate 10 having L-shaped brackets 11 each bolted or otherwise attached thereto by one

of the webs of each as shown at 12 with the other webs directed vertically and in spaced relation as shown. The vertical webs of the brackets are provided with inwardly directed stops or spurs 13. A mast 14 is disposed at its lower end between the vertical webs of the brackets and is provided with seats or sockets to receive the studs 13, by which means the mast is mounted to swing into a vertical or horizontal position, as required.

At its upper end the mast 14 is provided with a casing 15 in which a fabric member 16 of red or other color may be rolled or unrolled, as required. The casing 15 is provided with a hook 17 to which a signal lantern, indicated at 18, may be suspended for night signalling.

The roller within the casing is not shown, as it forms no part of the present invention. The roller is provided with a crank 19 whereby it may be actuated.

The mast 14 is tubular and formed with a longitudinal slot indicated at 14', and slideable in the mast is an extension member 20, the base member 10 having an aperture 21 to permit the extension member to pass.

The extension member is provided with a clamp screw 22 operating through the slot 14' to provide means for holding the extension member in adjusted position or to lock it wholly withdrawn into the mast, as may be required.

The vertical webs of the brackets are reduced at their upper ends as shown at 23, and slidably disposed on the mast 14 is a collar 24 which is adapted to receive the reduced portions of the brackets, and thus lock the mast in vertical position. The collar 24 is provided with a set screw 25 operative to lock the collar in position on the mast.

Pivoted to the lower web of each of the brackets is a bar 26, the pivots being preferably two of the bolts 12 by which the brackets are attached to the base member 10, as shown. The bars 26 are preferably L-shaped transversely and at their outer ends are provided with "toe members" 27 adapted to be forced between one of the fish plates 28 and the webs of the rails 29, as represented in Figures 1 and 2.

The bars 26 are connected intermediate their ends by a link 30, the latter pivoted at one end at 31 to one of the bars 26 and de-

tachably coupled at the other end at 32 to the other bar. The bar to which the link is detachably coupled is provided with a plurality of apertures 33 for the bolt 32, so that 5 the bars 26 may be adjustably coupled to enable them to be fitted to fish plates of varying lengths.

By this arrangement the bolt 32 may be detached and the link 30 turned laterally 10 into the position shown by dotted lines in Figure 2, and the rail engaging ends of the bars moved toward each other when not in use, and secured in their closed position by a hook 34 or like device. By this means the 15 device may be folded for transportation or storage.

Pivoted at 35 to one of the bars 26 externally of the base member 10 and its brackets 11 is a bar 36 having a longitudinally directed slot 37 to receive a clamp bolt 38 in 20 the other bar 26.

By this means the bars may be firmly locked in distended position.

The average roadbed adjacent to the rails 25 and ties of railway lines is below the level of the rails to a greater or lesser extent, and the extension member 20 enables the device to be easily supported with the bars 26 in a horizontal position and the mast 14 in a 30 vertical position regardless of the distance below the level of the rails.

The tubular mast 14 is shown square, transversely, with the interior also square, and the member 20 correspondingly square, 35 but the mast and stay members may be round or in other form as required, or arranged as shown in Figure 8 with the member 20 slideable upon the member 14 and guided by sleeves or collars 39 and held by 40 a set screw 40.

It is not desired to limit the invention to any specific form of the mast and its extension member 20.

In practice the bars 26 will be about five 45 feet or more in length to hold the mast at that distance from the nearest rail so that the passing trains will not strike the mast, and the mast will be of sufficient length to hold the signal flag about five feet above 50 the upper lines of the rails, but these dimensions may be varied as required.

The improved device is simple in construction, may be made wholly of metal, and as 55 light as possible consistent with the strains to which it will be subjected.

The improved implement when folded may be transported with the other tools or apparatus employed by the track repairers or others, and will be found very convenient for 60 the purposes described.

The preferred embodiment of the invention is disclosed in the drawings and set forth in the specification, but it will be understood that modifications within the scope 65 of the claimed invention may be made in

the construction without departing from the principle of the invention or sacrificing any of its advantages.

Having thus described the invention what is claimed as new is:

1. A signal support comprising a base member, bracket devices attached to said base member and including vertical portions having studs extending from their confronting faces, a mast mounted to swing upon said studs and adapted to carry a signal device, means for locking said mast to said brackets, an extension member, means for locking said extension member adjustably to said mast, bars swingingly connected at their outer portions to said brackets and adapted to be coupled at their inner ends to a railway rail, and means for locking said bars to said railway rail.

2. A signal support comprising a base member, bracket devices attached to said base member and including vertical portions, a mast mounted to swing between said brackets and adapted to carry a signal device, means for locking said mast to said brackets, an extension member, means for locking said extension member adjustably to said mast, bars swingingly connected at their outer portions to said brackets and adapted to be coupled at their inner ends to a railway rail, and means for locking said bars to said railway rail.

3. A signal support comprising a base member, bracket devices attached to said base member and including vertical portions, a mast mounted to swing between said brackets and adapted to carry a signal device, a collar enclosing said bracket and operating to lock the mast therebetween, an extension member, means for locking said extension member adjustably to said mast, bars swingingly connected at their outer portions to said brackets and adapted to be coupled to their inner ends to a railway rail, and means for locking said bars to said railway rail.

4. A signal support including coacting brackets, a mast carrying signal devices and swinging between said brackets, means for locking said mast to said brackets, an extension member, means for locking said extension member adjustably to said mast, bars swingingly connected at their outer ends to said brackets and adapted to be coupled at their inner ends to a railway rail, and means for locking said bars to said railway rail.

5. A signal support including coacting brackets, a mast carrying signal devices and swinging between said brackets, means for locking said mast to said brackets, an extension member, means for locking said extension member adjustably to said mast, bars pivotally coupled to said brackets and adapted to be detachably coupled to a railway rail, a slotted locking member pivoted at one end to one of said bars, and a clamp device 130

engaging the other bar and operating through the slot of the locking member.

6. A signal support including coacting brackets, a mast carrying signal devices and swinging between said brackets, means for locking said mast to said brackets, an extension member, means for locking said extension member adjustably to said mast, bars pivotally coupled to said brackets and adapted to be detachably coupled to a railway rail, a slotted locking member pivoted at

one end to one of said bars externally of the brackets, a clamp device engaging the other bar and operating through the slot of the locking member, and a link pivoted at one end to one of the bars and inwardly of the brackets, and means for detachably coupling the link at the other end to the other bar. 15

In testimony whereof, I affix my signature hereto.

JOEPH M. CONLEY.
